UNITED STATES PATENT OFFICE.

GRANVILLE KIMBALL AND HENRY S. TEAL, OF CHICAGO, ILLINOIS.

FLUID-PRESSURE GOVERNOR.

SPECIFICATION forming part of Letters Patent No. 449,222, dated March 31, 1891.

Application filed June 5, 1890. Serial No. 354,408. (No model.)

To all whom it may concern:

Be it known that we, GRANVILLE KIMBALL and HENRY S. TEAL, citizens of the United States, residing at Chicago, in the county 5 of Cook and State of Illinois, have invented a certain new and useful Improvement in Fluid-Pressure Governors, which is fully set forth in the following specification, reference being had to the accompanying drawing.

10 This invention relates to a fluid-pressure governor especially designed to be used in connection with a steam-pump for the purpose of preserving any desired head or pressure of water by automatically cutting off the supply of steam when such head is reached and turning it on again whenever the pressure of the water falls below the predetermined maximum. It is common to use for this purpose the ordinary fluid-pressure regulator, which is interposed in a steam-pipe to maintain a certain steam-pressure on the delivery side, regardless of the variations upon the induction side thereof. These latter devices furnish an even pressure of steam to 20 the pump, it is true; but the source from which the pump draws the water is usually far from regular. Thus in cities the pressure of the water in the mains varies constantly, being greater at one hour of the day than another, and always liable to be raised or lowered by a thousand different causes. If the pump receives the same steam-pressure at all times the water-pressure delivered by the pump will rise and fall with the pressure in 25 the mains or other source of supply.

30 The present invention contemplates the regulation of the steam-supply by the pressure of water delivered by the pump; and it consists in certain improved mechanism therefore, which is fully described below, and defined in the following claim.

The drawing furnished herewith shows a central vertical section of a governor embodying our invention. Referring thereto, it 35 will be seen that the body of said governor consists of a valve-casing A, provided with a central steam-port a and induction and education ports a' and a², respectively. A valve B rests upon a seat in the central opening a,

and is actuated by a stem b to open or close 50 the passage through the governor.

Upon the valve-casing is mounted by means of legs C a diaphragm-casing D, inclosing a chamber d between itself and a diaphragm E, of rubber or other similar material. Said 55 diaphragm is attached to the valve-stem b by means of nuts g g', threaded thereto, washers being interposed to protect the diaphragm.

At the point where the valve-stem leaves the valve-casing a stuffing-box H is provided 60 to prevent leakage, and as near as convenient to the box a bridge I unites the legs C C, furnishing a support for a spring J, coiled about the valve-stem and compressed between the bridge and a nut K, threaded to the stem. A 65 lock-nut L may also be used, as shown. A second bridge M extends across just beneath the diaphragm, and below it a nut N is also threaded to the stem. In attaching the governor to the pump the valve-casing is inter- 70 posed in the steam-pipe, with the induction side next to the cylinder, and a connection with the delivery-pipe of the pump leads the water into the chamber d through a port d'. The drawing shows the valve closed. To 75 start the pump, the nut N is first turned away from the bridge M as far as the valve is to open, but no farther, as this nut is designed to protect the diaphragm from an upward thrust of the valve-stem. The spring J is 80 then compressed by means of the nut K until its force overcomes whatever pressure the water in chamber d may exert upon the diaphragm. The valve now opens and allows the steam to work the pump. As soon as the 85 desired head is obtained the spring J should be released until it just balances the water-pressure on the diaphragm. This fixes the water-pressure which will be maintained, as the spring J will open the valve and admit 90 more steam whenever the pressure falls, or will be compressed to close the valve and cut off the steam whenever the pressure rises.

It is convenient at times in the use of these governors to be able to furnish a constant 95 and even steam-pressure to the pump, and we have made provision for this by boring the valve-stem to form a connection between

the eduction side of the valve-casing and the chamber *d*. When the water-pressure is used in this chamber, the bore is closed by a screw-plug *b'*. To use the steam-pressure, this plug 5 should be removed and the port *d'* plugged.

We claim as new and desire to secure by Letters Patent—

In combination, the valve-casing and valve, the isolated diaphragm - casing and dia- 10 phragm, the connecting valve-stem bored to

form a possible connection between the in- teriors of the two casings, and a screw-plug *b'*, adapted to close the bore in the valve- stem, substantially as described.

GRANVILLE KIMBALL.
HENRY S. TEAL.
